[57] CLAIM

The ornamental design for a floating jig, as shown and described.

DESCRIPTION

FIG. 1 is a perspective view of a floating jig, showing my new design;

FIG. 2 is a side elevational view, the opposite side being a mirror image thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a perspective view of a second embodiment;

FIG. 8 is a side elevational view, the opposite side being a mirror image thereof;

FIG. 9 is a top plan view thereof;

FIG. 10 is a front elevational view thereof;

FIG. 11 is a bottom plan view thereof; and,

FIG. 12 is a rear elevational view thereof.

The broken line showing of environment in FIGS. 1 and 7 is for illustrative purposes only and forms no part of the claimed design.
